DESIGN FOR A FOOT PUMP

Jean Otis Reinecke, Oak Park, Ill., assignor to
Vestal Chemical Company, St. Louis, Mo., a cor-
poration of Missouri

Application March 20, 1941, Serial No. 99,745

Term of patent 14 years

To all whom it may concern:

Be it known that I, Jean Otis Reinecke, a citizen of the United States, residing at Oak Park, Cook County, Illinois, have invented a new, original, and ornamental Design for a Foot Pump, of which the following is a specification, reference being made to the accompanying draw-

ing, forming a part thereof, in which Figure 1 is a plan view and Figure 2 is a side elevational view of a foot pump embodying my new design.

I claim:

The ornamental design for a foot pump, substantially as shown.

JEAN OTIS REINECKE.
